CLAIM

The ornamental design for an injection device, as shown and described.

DESCRIPTION

FIG. 1 is a perspective view of a first embodiment of an injection device showing the new design;
FIG. 2 is a front elevation view thereof;
FIG. 3 is a rear elevation view thereof;
FIG. 4 is a side elevation view thereof;
FIG. 5 is an opposite side elevation view thereof;
FIG. 6 is a top view thereof;
FIG. 7 is a bottom view thereof;
FIG. 8 is an environmental view thereof showing insertion or removal of a pharmaceutical product cassette; and
FIG. 9 is an environment view thereof showing the pharmaceutical product cassette inserted in the injection device.

FIG. 10 is a perspective view of a second embodiment of an injection device showing the new design;
FIG. 11 is a front elevation view thereof;
FIG. 12 is a rear elevation view thereof;
FIG. 13 is a side elevation view thereof;
FIG. 14 is an opposite side elevation view thereof;
FIG. 15 is a top view thereof;
FIG. 16 is a bottom view thereof;
FIG. 17 is an environmental view thereof showing insertion or removal of a pharmaceutical product cassette; and,
FIG. 18 is an environment view thereof showing the pharmaceutical product cassette inserted in the injection device. The dashed lines immediately adjacent to the shaded areas in the figures represent the boundaries of the claimed design. The dashed lines in the figures illustrate the portions of the design that form no part of the claimed design. None of the broken lines form any part of the claimed design.
